LEATHER NOVELTY GLOVE

Morris E. Goldstein, Denver, Colo.

Application June 14, 1943, Serial No. 490,937

3 Claims.

(Cl. 46—1)

This invention relates to an improvement in leather novelties and has reference more particularly to a catcher's miniature glove.

Novelties which are sold as souvenirs are manufactured in large quantities in connection with various games, such as football, basket ball and rodeo. Such novelties are ordinarily bought by visitors and spectators for souvenirs.

It is the object of this invention to produce a leather novelty in the form of a catcher's miniature glove to be sold as a souvenir at baseball games.

This invention, briefly described, consists of a catcher's miniature glove of an ornamental design, the palm portion of which is provided with an opening. A miniature baseball is secured to the glove by means of an elastic passing through the opening.

Having thus briefly described the invention, the same will now be described in greater detail, and for this purpose reference will be had to the accompanying drawing in which the invention has been illustrated, and in which:

Figure 1 is a front elevation of the miniature glove which forms the subject of this invention;

Figure 2 is an edge or side elevation thereof;

Figure 3 is a section taken on line 3—3, Figure 1;

Figure 4 is a section taken on line 4—4, Figure 3; and

Figure 5 is a section taken on line 5—5, Figure 1.

In the drawing reference numeral 10 designates the back of the glove and reference numeral 11 the front or palm thereof. The two parts 10 and 11 are cut into a shape roughly resembling that of a glove or mitten and are sewed together by means of a lacing member 12. Positioned on the inside of the glove is a wad of cotton or other stuffing material 13, which gives the back thereof a rounded appearance. The palm 11 is provided with an opening 14, through which a short elastic 15 extends. On the inside of the glove is an anchoring member 16. This member has opposed notches 17 for positioning the elastic 15. A ball 18 having the appearance of a miniature baseball is attached to the elastic by some suitable means. The elastic is very short and normally holds the ball against the outer surface of the palm in the manner shown in Figure 3, but permits the ball to be pulled away from the glove into the position shown in Figure 5. When the ball is released from the position shown in Figure 5, it snaps back into the

depressed area surrounding the hole 14 and this produces a sound similar to that heard when a ball strikes a catcher's glove.

Attention is called to the fact that the anchoring means 16 is inserted through the open wrist portion of the glove and can be removed and manipulated, if it should be found necessary to replace a broken elastic. The removable and replaceable anchoring member 16 also serves as convenient means for assembling the parts during manufacture. If the elastic should break, the anchoring member 16 will be held in the glove by the action of the cotton or other stuffing 13.

A miniature glove like that described can be attached to the wearer's garment by means of a suitable pin and can also have the name and date of the game printed on the outer surface, if desired.

Particular attention is called to the use of the miniature ball and to the manner in which it is secured to the glove whereby it can be manipulated to produce a sound imitating that given when the ball strikes the catcher's glove or mitten.

Having described the invention what is claimed as new is:

1. A leather novelty comprising a catcher's miniature glove, the palm portion having an opening, the outer surface about the opening having a depressed area forming a seat for a ball-like member, a ball-like member, an elastic having one end attached thereto, the other end passing through the opening, and means for anchoring the other end within the glove.

2. A leather novelty comprising a catcher's miniature glove, an anchoring element removably positioned in the glove, the palm portion having a hole, a ball-like member outside of the glove, and an elastic having one end secured to the ball-like member and the other to the anchoring element.

3. A leather novelty comprising two pieces of flexible material cut in the shape of a catcher's glove and attached to each other along the edges except that part representing the wrist portion, that part corresponding to the palm having an opening, an elastic element passing through the opening, means for anchoring the end within the glove, and a ball-like member attached to the other end of the elastic, the latter serving to hold it normally in engagement with the palm portion while permitting it to be moved away therefrom.

MORRIS E. GOLDSTEIN.
